UNITED STATES PATENT OFFICE.

GEORGE L. SMITH, OF MANCHESTER, NEW HAMPSHIRE.

EVENING AND GRADING MACHINE.

Application filed February 7, 1928. Serial No. 617,521.

This invention relates to machines for measuring the thickness of pieces of sheet stock, such as heel lifts, cut soles, and the like, and marking, evening, or distributing such pieces in accordance with the thickness determinations made by the measuring mechanism.

It is now the usual practice to even and grade heel lifts and cut soles prior to incorporating these parts in a shoe. This operation is usually performed in what is known as an evening and grading machine and such a machine comprises a mechanism for determining variations in thickness in each individual piece of stock, and means for skiving the stock to substantially the thickness of the thinnest portion found by said measuring mechanism. Such a machine usually includes also some means for grading the pieces of stock so skived, this grading operation usually consisting either in marking a grade designation on each piece of stock, or in so distributing pieces of stock that the pieces having substantially the same thickness will be thrown into a given bin or container.

The present invention will be herein disclosed as embodied in a machine which automatically feels for the thinnest spot in a given area of stock, skives the stock to a thickness equal to that of said thinnest spot, and then distributes the pieces of stock so acted upon in accordance with their final thicknesses. The invention has for its chief object to devise a machine of the general character above indicated which will be more accurate than machines of this type previously proposed, will operate more rapidly than prior machines, and will generally be an improvement on machines of this character as heretofore constructed.

The nature of the invention will be readily understood from the following description when read in connection with the accompanying drawings, and the novel features will be particularly pointed out in the appended claims.

Referring now to the drawings,

Figure 1 is a side elevation of a machine constructed in accordance with the present invention;

Fig. 2 is a plan view of the machine shown in Fig. 1;

Fig. 3 is a front elevation of the machine shown in Figs. 1 and 2, certain of the parts

of the casing being broken away to illustrate the mechanism enclosed therein;

Fig. 4 is a vertical cross sectional view on the line 4—4, Fig. 2;

Fig. 5 is a vertical cross sectional view on the line 5—5, Fig. 3;

Fig. 6 is a plan view of the magazine in which the heel lifts are stacked;

Fig. 7 is a side elevation of the magazine;

Fig. 8 is a plan view of a portion of a distributing mechanism with which the machine may be equipped;

Fig. 9 is a side elevation of the parts shown in Fig. 8;

Fig. 10 is a side elevation of another part 70 of the distributing mechanism;

Fig. 11 is a plan view showing the manner in which the feelers or presser feet act on a heel lift;

Fig. 12 is a cross sectional view on the 75 line 12—12, Fig. 11;

Fig. 13 is a side elevation of the bucket which preferably is used in the distributing mechanism; and

Fig. 14 is an end view of a part of the 80 distributing mechanism.

The machine shown comprises a magazine in which a supply of heel lifts or other pieces of stock to be operated upon is held, a feeder that feeds such pieces of stock one 85 at a time out of the magazine, a feeler mechanism to which the pieces of stock are delivered by the feeder and which detects the thinnest portion in a given area of the stock, and a skiving mechanism which evens the 90 pieces of stock. Suitable connections are provided between the skiving mechanism and the feeler mechanism so that the skiving mechanism reduces the stock to the thickness of the thinnest portion acted upon by the 95 feelers. A distributing mechanism under the control of the feeler mechanism then distributes the skived pieces of stock to containers, each container receiving only pieces of stock of a given thickness. The detailed 100 description of the several mechanisms of the machine will be taken up in substantially the order in which they have just been mentioned.

The machine shown is designed especially 105 to handle leather lifts from which heels are built, and consequently it includes a magazine adapted to hold a stack of these heel lifts. Referring more especially to Figs. 4, 6 and 7, it will be seen that the magazine 110

comprises a frame which includes base pieces 2-2 and an upright front 3. This front 3 is slotted and has ways formed in it to receive slides 5 and 6, Fig. 4, which are secured to a thin vertical bar 7 that engages the stack of lifts L, Fig. 6, at one side thereof and near the breast corners of the lifts. Another bar 8 similarly affords lateral support for the opposite side of said stack and is secured to upper and lower slides like the slides 5 and 6. One of the former slides is shown at 9. The breast edges of the lifts L are supported by bars that form a part of the front 3 of the magazine. For the purpose of adjusting the two pairs of slides toward and from each other, the upper slides 5 and 9 are mounted on reversely threaded portions of a screw threaded shaft 12, while the lower slides are mounted on a similar shaft 13. Consequently, when these shafts are turned, the side bars 7 and 8 are moved toward or from each other, depending upon the direction of rotation of the shafts. The two shafts 12 and 13 have bevel gear connections with a vertical shaft 14, Fig. 7, and the upper shaft 12 carries a hand wheel 15 by means of which it may be rotated to adjust the bars 7 and 8.

The rearward edges of the lifts L are supported by a V-shaped plate or bar 16 secured to a plate 17 which is adjustable backward or forward in ways formed in the base pieces 2-2. Two inclined pieces 18 and 19 are secured in the lower part of the bar 16 where they tend to crowd the lifts forward as the lifts drop into the lower part of the magazine. The entire magazine is secured to a horizontal table or plate 20 which forms a part of the machine frame and is rigidly secured to the other frame members.

The mechanism for feeding the lifts out of the magazine comprises a feed slide 22, best shown in Fig. 4, mounted to reciprocate in a horizontal way formed in parts that are secured rigidly to the table 20. A feed dog 23 is pivoted to the slide 22 and is normally held in a raised position by means of a spring 24, it being understood that the table 20 is slotted to permit the dog to project therethrough. For the purpose of reciprocating the feed slide 22, it is pivoted to the upper end of a lever 25 which is fulcrumed at 26 and has a guideway formed therein to receive a block 27 which is mounted on a pin 28 projecting from the face of the gear 30. This gear is secured fast on a shaft 31 and meshes with a pinion 32 secured on a horizontal shaft 33 which projects through the machine from one side to the other, (see Fig. 2). This is the main driving shaft of the machine and it carries a pulley 34 by means of which it may be belted to any convenient source of power.

As the feed dog 23 is moved forward by the mechanism just described, the hook on

said dog engages the rearward edge of the bottommost lift in the magazine and carries this lift forward out of the magazine. The dog preferably is made double, as best shown in Figs. 2 and 3, so that it engages the edge of the lift at points on opposite sides of its median line. There is some tendency for the lift next above the bottommost lift to move forward with the latter lift, and in order to effectually prevent the feeding of two lifts at a time, the magazine is provided with a gate 36, Fig. 4, which extends down to a point closely adjacent to the upper surface of the table 20. This gate is pivoted at its upper edge, and springs, one of which is shown at 38, Fig. 7, act on the gate at its opposite ends to hold it yieldingly in its vertical or closed position. These springs are anchored to horizontal arms 37-37, Figs. 6 and 7, which are pivoted at 39-39 to opposite sides of the magazine base. The gate 36 is pivoted to these arms 37-37 at 40, and in addition to having a pivotal movement it can also have an up and down movement due to the connection just described. It is normally held down, however, by means of one or more spring pressed plungers 42, Fig. 4, which bear on the upper edge of the gate, these plungers being mounted in the front 3 of the magazine.

The feeding mechanism above described carries the bottommost lift of leather out of the magazine and presents it to the feeler mechanism. This mechanism, as best shown in Figs. 3, 4, 11 and 12 comprises a series of independently movable feelers 44 so arranged that they engage the entire marginal portion of a lift L of leather. The feelers preferably are arranged in right and left groups, as shown in Figs. 3 and 11, the two groups acting on opposite margins of the lift. Each feeler, as best shown in Fig. 3, is connected by two links 45-45 to the shank of an L-shaped bracket 46 so that it can move freely up and down but cannot tip. Two such brackets 46 are provided, one supporting each group of feelers, and the two brackets are secured to a plate 47 by means of bolts passing through slots in the plate so that the two groups of feelers may be adjusted toward or from each other. Each feeler is normally held in a depressed position by means of a spring 48 which is interposed between a shoulder on the feeler and a portion of the bracket 46, as clearly shown in Fig. 3, the spring being held against buckling by means of a rod that extends axially through it and is secured at its upper end in the bracket and is guided at its lower end in a hole in the feeler. The slots in which the links 45 move limit the downward movement of the feelers.

The plate 47 and the brackets 46-46 form what may be termed a feeler head in which the feelers 44 are supported for vertical

movement independently of each other. The feeler head can reciprocate vertically and it is guided by four pins 50 secured to the plate 47 at points adjacent to its four corners, the pins being mounted to reciprocate in sockets secured to a part of the machine frame. One of said sockets is shown at 51, Fig. 5.

For the purpose of moving the feelers up and down into and out of engagement with a lift of leather which has been fed under them, the feeler head is connected by links 52, Figs. 1, 2 and 5, to short arms 53—53 keyed to a rock shaft 54 which is supported in brackets 55—55. This rock shaft also has another arm 56, Fig. 1, secured thereto, which is pivotally connected with the upper end of a rod 57 that projects freely through a hole in the end of a lever arm 58. A strong spring 60 is interposed between the arm 58 and a nut on the lower end of the rod 57, while a tube 61 is interposed between the arm 58 and the pivot head 62 through which the rod 57 is joined to the arm 56. The tube 61 encircles the rod 57 and acts as a spacing device to maintain at all times a minimum tension on the spring 60.

The arm 58 is one arm of a bell crank lever fulcrumed at 63, and another arm 64 of this lever carries a roll 65 which runs on the periphery of a cam 66 fast on a shaft 59 driven by gear connections with the shaft 33 previously referred to. A third arm 67 of the bell crank lever carries a roll 68 which runs on the periphery of another cam 70, also secured fast on the shaft 59. Consequently, as the high part of the cam 66 moves under the roll 65, it depresses the arm 58, thus acting through the connections above described to move the feelers downwardly into contact with the stock. The pressure with which this mechanism moves the feelers into contact with the work depends on the degree to which the spring 60 is compressed. The feelers, however, are pressed firmly against the lift L of leather, each feeler yielding upwardly against the pressure of its individual spring 48 as the feeler head continues to move downwardly.

It will now be clear that each feeler takes a position during the feeling operation which depends upon the thickness of the particular part of the lift that it engages. Fig. 12 shows approximately the relative positions which the feelers may be expected to assume in feeling of a typical lift. The lift is supported on the table 20 during this operation, and the cam mechanism gradually brings the feelers down on to the lift and then increases the pressure on them up to a certain maximum, maintaining this maximum pressure for a substantial period of time. The roll 65 then passes off from the high portion of the cam 66, and the cam 70 next acts through the roll 68 and lever arm 67 to raise the

feelers out of engagement with the lift of leather which has just been acted upon.

The lift which has now been subjected to the action of the feeler mechanism is next advanced or fed forward to a skiving or evening mechanism. This feeding movement is effected by a dog 72 pivoted to the feed slide 22 and normally held in a raised position by means of the spring 24 previously referred to. During the backward stroke of the feed slide, the pawl or dog 72 is depressed by its contact with the lift which is then being acted upon by the feeler mechanism, but it rises as soon as it passes out from under this lift so that upon the next forward stroke of the feed slide it will push this lift of leather forward to the evening mechanism.

The evening mechanism comprises upper and lower rolls 74 and 75, respectively, the upper roll preferably having a roughened or milled peripheral surface to enable it better to grip the lifts of leather. This upper roll is supported at its opposite ends in bearing blocks which are mounted to slide in vertical guideways, each block being depressed by a strong spring 76. The movement of each block under the influence of the springs 76—76 is limited by a bolt 77 which is fastened in the block and projects upwardly through the housing for the spring and has nuts 78—78 threaded thereon. The lower roll 75 is similarly supported at its opposite ends in blocks 80 mounted to slide in vertical guideways formed in the machine frame, and each block is normally held in a raised position by means of a coiled spring 81. The springs 81 are made very much lighter than the springs 76 so that when a lift of leather is fed between the rolls 74 and 75 the lower roll 75 will yield, while the upper roll remains in substantially a fixed position, so far as bodily movement is concerned, until the depression of the lower roll is arrested. The two rolls just mentioned feed the stock against the edge of a stationary knife 82 secured by screws 83 in a knife holder 84 which is fixed in the machine frame.

For the purpose of driving the upper roll the main shaft 33, previously referred to, has a sprocket 86 mounted on one end thereof and this sprocket is connected by a chain, indicated diagrammatically at 87, Fig. 1, and shown more in detail in Figs. 2 and 3, with another sprocket wheel 88 mounted 115 on a shaft 89 which also carries a gear 90 meshing with another gear 91 which is secured to the shaft of the roll 74. The lower roll 75 is driven through a gear 206, Figs. 2 and 3, which is secured directly to the 120 shaft of the roll, this gear meshing with a floating pinion 207 which, in turn, meshes with a pinion 208 secured on the main shaft 125

33. Links 209 and 210 support the shaft on which the floating pinion 207 rotates, and guide this pinion.

As above stated, connections are provided between the feeler mechanism and the evening mechanism to enable the former mechanism to control the operation of the latter mechanism. The control is such that the evening mechanism splits or skives each lift 10 of leather to a thickness equal to that of the thinnest portion of the lift engaged by the feelers. This connecting mechanism comprises two vertical plates 93—93 each mounted to move up and down and having 15 horizontal upper edges which engage, respectively, with the lower ends of the two groups of feelers. The plates are held in contact with the feelers by springs 94—94. The ends of one of the plates 93 are connected by links 95 and 96, Fig. 5, to sectors 97 and 98, respectively, which mesh with each other, while the two ends of the other plate are connected by links 99 and 100 to arms 101 and 102, respectively, that are rigidly secured to the respective sectors 97 and 98. The sectors are pivoted to frame members at 103 and 104, respectively, Fig. 5. This arrangement guides the two plates 20 93—93 for movement in parallel vertical paths and, at the same time, compels the two plates to move in unison.

When the feelers are brought down into contact with a lift of leather the plates 25 93—93 are depressed by their engagement with the feelers, the springs 94—94 holding the plates upwardly in contact with the feelers. The plates thus will be forced down to a position determined by the feeler which occupies the lowest position at this moment; or, in other words, by the feeler which is in 40 engagement with the thinnest portion of the lift. If a feeler of one group engages a thinner point than a feeler of the opposite group, the former feeler will control the vertical position of both plates 93—93 due to the link and sector connections described 45 above.

One of the plates 93 is connected by a 50 link 107, Figs. 1, 4 and 5, to a rack 108 which is mounted to slide in a vertical guideway. This rack meshes with a mutilated gear 109 which is secured to a rock shaft 110. The teeth of this gear at the opposite side of its axis from the rack 108 engage a toothed 55 slide 112 which is guided on a vertical pin or rod 114 that depends from one of the bearing blocks 80 for the lower roll 75. The rock shaft 110 also carries another gear meshing with a similar toothed slide 112 (not shown) guided on a pin that projects 60 from the opposite bearing block 80 for the roll 75. Consequently, as the plates 93—93 are depressed by one or more of the feelers 65 as they make their thickness determination, this movement is transmitted through the

rack 108 and gear 109 to the slides 112, setting these slides in a vertical position that depends upon the vertical position of the plates 93—93. This, in turn, depends upon the position of the feeler engaging the thinnest portion of the lift. It should be noted that this adjustment of the slides is made by the feelers. An arm 115, Fig. 1, carries a pawl 116 which engages the teeth of a rack or ratchet 117, this rack being secured fast to 70 one side of the machine frame. The pawl thus acts through the connections with the slides 112 to lock these slides in the positions to which they have been adjusted by their connections with the feeler mechanism. 80

The slides remain locked in their adjusted positions while the evening operation on a lift is being performed, and the pawl 116 is then moved out of engagement with the rack 117 and held out of engagement therewith 85 while the connections are being readjusted for the feeling operation on another lift. For this purpose the tail of the pawl 116 carries a pin 118, Fig. 1, which runs in a slot 119 formed in the head of a lever 120. 90 This lever is supported partly by a link 121 and partly by one arm of a lever 122 which is fulcrumed at 123 and carries a roll 124 running on the periphery of a cam 125. The high part of this cam swings the lever 95 122 in a counter-clockwise direction, Fig. 1, thus moving the pawl out of engagement with the rack 117.

It will now be understood that when the machine is in operation, each forward movement of the feeder will carry one lift out of the bottom of the magazine and present it to the feeler mechanism, at the same time carrying the lift which has just been subjected to the operation of the feelers forward to the evening mechanism. The feeling and evening operations are performed while the feeder makes its return or backward stroke. It may here be noted that as the feeder delivers a lift to the evening 110 mechanism, the feeder may move faster than the evening mechanism can take the lift, and in order to compensate for any difference in the natural travel of the feeder and the lift, the feed lever 25 preferably is mounted on 115 a yielding fulcrum. Referring to Fig. 4 it will be seen that the fulcrum 26 for this lever is on the end of a rod 128 which telescopes within a tube 129 pivoted on the frame at 130. A spring 131 is interposed 120 between the tube and the end of the rod 128 and tends to push the rod out of the tube, this movement, however, being limited by a screw or pin 132 which is set into the rod 125 and slides in a slot formed in the upper side of the tube. If the feed slide meets with any abnormal resistance, the eccentric pin 28, which operates the slide, will swing the lower end of the lever 25 toward the right, Fig. 4, thus compressing the spring 131 and 130

avoiding any breakage of the parts or damage to the lifts.

There is sometimes a tendency for the lifts to twist or turn in a horizontal plane as they are moved forward over the surface of the table 20. In order to overcome this tendency and to keep the lifts straight, a mechanism has been provided which may be used, if desired, and which comprises two toothed wheels 134—134, Figs. 4 and 7, arranged to engage the lifts as they are fed over the table. These wheels are mounted one in advance of the other, being supported between two plates 135 which are held in spaced relationship, and are pivoted to the forward arm 136 of a forked lever having side pieces 137—137 pivotally supported on the screws 39. One of the side pieces 137 has an extension 138 which is acted upon by a spring 139 in a direction operating to press the wheels 134 against each piece of stock as it is fed forward into position for the feeling operation.

When the lift which has just been released by the feelers is delivered to the rolls 74 and 75, the latter roll yields until its bearing blocks 80—80 strike the slides 112—112. This roll can yield no further since the slides are locked, and any other relatively yielding movement of the rolls which must take place in order to admit the lift, is produced by the upward movement of the roll 74 against the pressure of the spring 76—76. When the roll 75 has moved down to its lowermost position, the distance between the upper surface of this roll and the edge of the knife 82 is equal to the thickness of the thinnest portion of the lift acted upon by the feelers. The rolls force the lift against the edge of the knife, the part of the lift above the edge of the knife being severed from the body of the lift and thrown out above the upper surface of the knife, while the main part of the lift passes under the knife and over the roll 75.

This completes the feeling and evening operations, and for some purposes these are all the operations required on the stock. For most purposes, however, it is desired that the lifts, in addition to being evened, shall be graded in some manner. This may be accomplished by marking a grade indication, such as the thickness of the lift in irons, on the lifts after they have been evened, or by distributing the lifts so that those of equal thickness will be thrown together. The present machine includes a distributing mechanism.

This distributing mechanism includes a sector 142, see Figs. 5 and 9, secured on the rock shaft 110, previously referred to, and meshing with a mutilated gear 143 having an arm 144 extending therefrom and connected by a link 145 to a slide 146 mounted

for movement in a vertical guideway. This slide carries parts which form another guideway 147 in which a rod 148 is mounted to reciprocate horizontally. Normally this rod is held toward the left, Fig. 9, by means of a spring 150. It is moved in the opposite direction by its engagement with a part 151 depending from a slide 152 which is mounted in a horizontal guideway 153. This slide is held toward the left, Fig. 9, by a strong spring 154, and it is provided with a shoulder 155 which is adapted to be engaged by a roll 156 projecting eccentrically from a gear 157 fast on the shaft 59, see Figs. 3, 5 and 9. This gear is driven by a pinion 158 fast on the main shaft 33. The roll 156 is always on the right-hand side, Fig. 9, of the shoulder 155 and simply moves the slide 152 toward the left to a fixed point at each rotation of the gear 157. The slide is moved in the opposite direction, that is to the right, by the spring 154, and this movement is transmitted through the rod 148 to a stepped plate 160 fixed to a slide 161 which is mounted to reciprocate in a guideway formed in a frame part 162.

The length of the stroke thus imparted to the stepped slide 160 will depend upon the particular step engaged by the end of the rod 148; and this, in turn, will depend upon the elevation of the slide 147. The vertical adjustment of this slide, as above stated, is controlled by the connections with the rock shaft 110, and this depends upon the position of the feelers.

Secured to the stepped plate 160 is a rack 163, see Figs. 9 and 10, which meshes with a gear 164 secured on a shaft 165. Another gear 166 secured on this shaft meshes with a vertical rack 167 which carries a pin 168 that engages a shoulder on a stepped slide 170. Links 171 and 172 connect opposite ends of this slide with arms 173 and 174 pivoted at 175 and 176, respectively, and having fastened thereto sectors 177 and 178 that mesh with each other. The stepped plate 170 is vertically guided by pin and slot connections with stationary parts of the machine, one such pin being shown at 181, and the plate is normally held at the upper limit of its movement by means of a spring 180 which connects the arms 173 and 174. These parts, including the sectors, prevent any binding or tipping of the stepped plate and compel it to move in a straight vertical line.

The steps on the plates 160 and 171 are graduated in a definite manner, say for instance, by irons; and the arrangement is such as will be evident from the foregoing description of structure, that as the feeler mechanism makes a thickness determination on a given lift and controls the operation of the evening mechanism on that particular lift, it likewise effects, through a portion

of the same connecting mechanism by which such control is effected and through the additional mechanism just described, a movement of the plate 170 into an elevation dependent upon the thickness of the thinnest portion of the stock engaged by the feelers. The adjustment of the plate 170 is effected substantially simultaneously with the adjustment of the evening mechanism.

10 As the lift which has just been evened is fed out under the knife 82, it slides down over a short inclined apron 183, Figs. 5 and 10, and drops into a distributor or bucket 184. The rear wall 185 of the bucket is 15 pivoted within the body of the bucket at 186, Fig. 10, in such a manner that its lower end normally rests against the front of the bucket and thus keeps the bucket closed; and the weight of this movable wall is sufficient 20 to hold it in its closed position notwithstanding the weight of a heel lift in the bucket.

The bucket is supported by two horizontal rods 187 and 188 between which it is mounted, the bucket being secured at one side to a slide 25 189 which runs on the rod 187; and at its opposite side carrying a wheel 190 that runs on the rod 188. For the purpose of moving the bucket backward and forward to deliver the lift which it carries to the desired point, 30 the bucket is connected by means of a link 191 with the upper end of a lever 192, Figs. 10 and 14, which is fulcrumed on the pin 193. Loosely mounted on this pin is a short arm or lever 194, the upper end of which 35 is connected by means of a long rod 195, Figs. 10, 14 and 2, to a block 196 which is pivoted on an eccentric pin projecting from a disk 197 which rotates with the gear wheel 30 previously referred to. This mechanism 40 oscillates the arm 194 in a path of fixed length, and the arm 194 carries an extension or finger 198, Fig. 14, which lies back of the lever 192 and returns this lever at each oscillation of the arm 194 to the extreme right-hand limit of its movement, as shown in Fig. 45 10. The two levers 194 and 192 are connected by a coiled spring 200, Fig. 14, which is so tensioned that it tends to hold the lever 192, in contact with the finger 198, or, in 50 other words, to make the two levers move in unison as the lever 194 swings toward the left, Fig. 10.

Assuming now that a heel lift has just 55 been measured by the feeler mechanism, skived, and delivered to the bucket or distributor 184, and that the stepped plate 170 has been adjusted, as previously described, to a height determined by the thickness of the thinnest portion of the stock engaged 60 by the feelers; the next operation consists in moving the bucket forward through the mechanism just described, the spring 200 producing this movement. At some point in the forward or left-hand movement, Fig. 65 10, of the bucket, which point will be de-

termined by the vertical position of the plate 170, an extension 201 projecting laterally from the lower end of the movable part of the bucket will strike one of the steps on the plate; and, as the bucket continues to move forward, the movable wall 185 of the bucket will be swung into its open position, as shown in Fig. 13, thus releasing the lift carried by the bucket and allowing this lift to slide edgewise through the bottom of the 75 bucket. This will result in discharging the lift into one of the chutes 203, Fig. 10, formed in an inverted hopper 204, over the top of which the bucket moves. These 80 chutes lead to containers (not shown) which receive the lifts. As the arm 194 swings backwardly, the finger 198 will engage the lever 192 and return this lever, and with it the bucket, to their original positions.

It will thus be clear that each lift immediately after it is skived will be distributed to one of the chutes 203, lifts of the same thickness being delivered to the same chute, and all the operations of feeding, feeler, skiving and distributing being performed automatically. The only attention that the machine requires during its operation is to keep the magazine supplied with lifts and to take the lifts away as the containers become filled.

Due to the fact that two lifts are always 95 in the machine while it is in operation, the machine operates very rapidly, it being remembered that the thickness determination is being made on one lift while another lift is being skived and distributed. The fact 100 that the feelers are located closely adjacent to each other and engage the entire outer marginal surface of the heel lifts, ensures much greater accuracy of measurement, and consequently of evening, than has been possible in any prior machine of which I have 105 been able to learn. A further condition contributing to the accuracy of the measurements made by this machine, is the fact that the thickness determinations are made while 110 the lift is stationary and is supported on a rigid surface. Errors which otherwise would 115 be introduced by momentum of the parts, therefore, are eliminated.

In the specific machine above described, 115 the feelers are arranged to engage only the marginal portion of a lift, and each lift subsequently is skived to the thickness of the thinnest portion of this margin. It is possible 120 that there may be a thinner spot in the central part of the lift, and, if desired, the feelers could be arranged to measure the thickness of the central portions of the lift as well as the marginal portions. This usually 125 is not necessary or desirable, however, because a thinner spot in the central part of the lift is immaterial. But it is important that the margin of the lift be of a uniform thickness since, otherwise, when several of 130 these lifts are assembled to form a heel, the

irregularities in thickness will result in producing a heel which is thicker on one side than on the other.

It will readily be appreciated that the invention may be embodied in a machine designed to act upon pieces of sheet stock of different shape from those specifically mentioned above, particularly cut soles, only minor changes in design being required for 10 this purpose.

While I have herein shown and described the best embodiment of my invention which I have so far devised, it will be evident that the invention may be embodied in other 15 forms without departing from its spirit or scope.

Having thus described my invention, what I desire to claim as new is:

1. In a machine of the character described, the combination of feeler mechanism for detecting variations in the thickness of a piece of sheet stock, said mechanism comprising a series of feelers arranged to engage the stock simultaneously, said feelers 20 being individually movable in conformity to the thickness of the portions of the stock engaged thereby and being operative to detect the thinnest portion of the stock so engaged, a magazine for holding a supply of 25 said pieces of stock, a rigid table for supporting the pieces of stock while they are engaged by said feelers, means for feeding the pieces of stock one at a time from said magazine over the surface of said table and 30 positioning them for engagement by said feelers, and additional means under control of said feeler mechanism and independent of said feeding means for subsequently treating said pieces of stock in accordance with 35 40 the thickness determinations made by said feeler mechanism.

2. In a machine of the character described, the combination of feeler mechanism for detecting variations in the thickness of a piece of sheet stock, said mechanism comprising a series of feelers arranged to engage the stock simultaneously and said feelers being individually movable in conformity to the thickness of the portions of the stock 45 engaged thereby, a magazine for holding a supply of said pieces of stock, mechanism under the control of said feeler mechanism for automatically treating the pieces of stock in accordance with the thickness 50 determinations made by said feeler mechanism, and mechanism for automatically feeding a piece of stock out of said magazine and presenting it to said feeler mechanism and for simultaneously advancing another 55 piece of stock previously acted upon by said feeler mechanism and feeding it to said treating mechanism.

3. In a machine of the character described, the combination of feeler mechanism

for detecting variations in the thickness of a piece of sheet stock, said mechanism comprising a series of feelers arranged to engage the stock simultaneously and said feelers being individually movable in conformity to the thickness of the portions of the stock engaged thereby, a magazine for holding a supply of said pieces of stock, mechanism under the control of said feeler mechanism for automatically treating the pieces of stock in accordance with the thickness determinations made by said feeler mechanism, two feeding devices operative one in advance of the other to feed a piece of stock out of said magazine into position to be acted upon by said feeler mechanism and to advance another piece of stock from said position to said treating mechanism, and a single operating mechanism for said feeding devices. 75 80

4. In a machine of the character described, the combination of feeler mechanism for detecting variations in the thickness of a piece of sheet stock, said mechanism comprising a series of feelers arranged to engage the stock simultaneously and said feelers being individually movable in conformity to the thickness of the portions of the stock engaged thereby, a magazine for holding a supply of said pieces of stock, mechanism under the control of said feeler mechanism for automatically treating the pieces of stock in accordance with the thickness determinations made by said feeler mechanism, a rigid table for supporting said pieces of stock while they are acted upon by said feeler mechanism, a feed slide mounted to reciprocate in said table, means for reciprocating said feed slide, and two feed dogs mounted on said slide, one in advance of the other, one of said dogs being operative to feed the pieces of stock one at a time out of said magazine and position them for the operation of said feeler mechanism, and the other feed dog acting simultaneously to carry a piece of stock from the feeler mechanism to said treating mechanism. 90 95 100 105 110

5. In a machine for treating pieces of sheet stock, the combination of mechanism for detecting variations in the thickness of a piece of said stock comprising a series of independently movable feelers, a common support for all of said feelers, springs acting individually on said feelers to hold them normally in a given relationship to said support but enabling them to be moved out of said relationship by contact with the stock, means for relatively moving said support and the stock to cause said feelers to make a thickness determination of said stock while the stock and feelers are relatively stationary, mechanism for evening the pieces of stock so acted upon, and connections between said feeler mechanism and said evening mechanism for automatically control-

ling the action of said evening mechanism in accordance with said thickness determination.

6. In a machine of the character described, 5 the combination with a stationary support for a piece of sheet stock, of mechanism for detecting variations in the thickness of said piece of stock comprising a series of feelers, a head in which said feelers are mounted for 10 movement independently of each other, means for moving said head toward and from said support, means for pressing said feelers individually against said piece of stock but enabling them to move independently of each other in conformity with variations in thickness of the portions of the stock engaged by the feelers, a skiving knife, two rolls for feeding the stock against the edge of said knife, said rolls being movable 20 toward and from each other, stops for limiting the movement of one of said rolls away from the other, and means arranged to be operated by said feelers for adjusting said stops in accordance with the thickness 25 terminations made by the feelers.

7. In a machine of the character described, a mechanism for detecting variations in the thickness of a piece of sheet stock comprising a series of independently movable feelers 30 arranged in two groups, said feelers being mounted closely adjacent to each other and positioned for the engagement simultaneously with the marginal portion of said piece of stock, and supporting means for said feelers enabling the two groups to be adjusted toward and from each other.

8. In a machine of the character described, the combination with a stationary support for a piece of sheet stock, of mechanism for 40 detecting variations in the thickness of said piece of stock comprising a series of feelers, a head in which said feelers are mounted for movement independently of each other, means for moving said head toward and from said support, means for pressing said feelers individually against said piece of stock but enabling them to move independently of each other in conformity with variations in thickness of the portions of the stock 50 engaged by the feelers, a part 93 arranged to be engaged and moved by the feeler engaging the thinnest portion of the stock, an adjustable skiving mechanism, and connections between said part 93 and said skiving mechanism for adjusting the setting of the skiving mechanism in accordance with the thickness 55 determination made by the feelers.

9. In a machine of the character described, a mechanism for detecting variations in the 60 thickness of a piece of sheet stock comprising a series of independently movable feelers, supporting means for the entire series of feelers, each feeler being connected with said supporting means by a pair of links, 65 and a spring for each feeler operative nor-

mally to hold the feeler in a given relationship to its support.

10. In a machine of the character described, the combination of a fixed table for supporting a piece of sheet stock, a series of feelers for engaging said stock, a head in which said feelers are mounted for feeling movement independently of each other, springs acting on said feelers individually to press them toward said support, 70 means for guiding said head for movement in a definite path toward and from said support, and power driven mechanism for moving said head toward said support, said mechanism including a spring through 75 which the movement of the power driven parts is transmitted to said head.

11. In a machine of the character described, the combination of feeler mechanism for detecting variations in the thickness of a piece of sheet stock, skiving mechanism for said pieces of stock comprising a knife and two rolls for feeding the stock against the edge of said knife, one of said rolls being 80 spring pressed toward the other, means for limiting the movement of said spring pressed roll away from its companion roll, and connections between said feeler mechanism and said means for adjusting said means in accordance with the thickness determinations 85 made by said feeler mechanism.

12. In a machine of the character described, the combination of feeler mechanism for detecting variations in the thickness of a piece of sheet stock, skiving mechanism for 100 said pieces of stock comprising a knife and two rolls for feeding the stock against the edge of said knife, one of said rolls being spring pressed toward the other, means for limiting the movement of said spring pressed roll away from its companion roll, connections between said feeler mechanism and said means for adjusting said means in accordance with the thickness determinations made by said feeler mechanism, and mechanism 105 for locking said means in its adjusted position.

13. In a machine of the character described, the combination of feeler mechanism for detecting variations in the thickness of a piece of sheet stock, skiving mechanism for said pieces of stock comprising a knife and two rolls for feeding the stock against the edge of said knife, one of said rolls being 110 spring pressed toward the other, means for limiting the movement of said spring pressed roll away from its companion roll, connections between said feeler mechanism and said means for adjusting said means in accordance with the thickness determinations made by said feeler mechanism, mechanism for locking said means in its adjusted position 115 during a substantially predetermined portion of the cycle of operations of the machine, and mechanism for subsequently un- 120

125 130

locking said means to permit said feeler mechanism to readjust said means.

14. In a machine of the character described, the combination of feeler mechanism for detecting variations in the thickness of a piece of sheet stock, skiving mechanism for said pieces of stock comprising a knife and two rolls for feeding the stock against the edge of said knife, one of said rolls being 5 spring pressed toward the other, stops for limiting the movement of said spring pressed roll away from its companion roll, connections between said feeler mechanism and said stops for adjusting the stops in accordance with the thickness determinations made 10 by the feeler mechanism, pawl and ratchet mechanism for locking said stops in their adjusted positions, and means for holding said pawl and ratchet mechanism unlocked 15 during a substantial portion of each cycle of operations of the machine.

15. In a machine of the character described, the combination of feeler mechanism for detecting variations in the thickness of a piece of sheet stock, a knife for skiving said pieces of stock, two rolls for feeding the pieces of stock against the edge of said knife, springs for pressing one of said rolls toward the other, means for limiting the 20 movement of said spring pressed roll away from the second roll, connections between said feeler mechanism and said means for adjusting said means in accordance with the thickness determinations made by said feeler mechanism, and springs for yieldingly 25 pressing said second roll toward its companion roll with a pressure materially greater than that exerted by the first mentioned springs.

16. In a machine of the character described, the combination of feeler mechanism for detecting variations in the thickness of a piece of sheet stock, said mechanism comprising a series of feelers individually 30 movable in conformity to the thickness of the portions of the stock engaged thereby, mechanism for feeding pieces of stock one at a time into position for the action thereon of said feelers, additional means for relatively moving said feelers and said sheet stock transversely of the plane thereof into operative engagement with each other to enable said feelers to make their thickness determination while said feelers and stock are 35 relatively stationary, a device arranged to engage a plurality of said feelers and to be moved thereby into a position determined by the feeler which engages the thinnest portion of the stock, additional mechanism for acting 40 on said pieces of stock after they have been subjected to the action of said feelers, and connections independent of said feeding mechanism for causing said device to control the operation of said additional mechanism.

17. In a machine of the character de-

scribed, the combination of feeler mechanism for detecting variations in the thickness of a piece of sheet stock, said mechanism comprising two groups of feelers arranged to engage the work simultaneously, said feelers being individually movable in conformity to the thickness of the portions of the stock engaged thereby, means for supporting the stock while it is engaged by said feelers, two devices mounted for engagement with the feelers of said respective groups and each arranged to be moved into a position determined by the feeler which engages the thinnest portion of the stock, additional mechanism for acting on the pieces of stock after they have been subjected to the operation of said feeler mechanism, and connections between said devices and said additional mechanism for controlling the operation of said additional mechanism in accordance with the thickness determinations made by said feelers.

18. In a machine of the character described, the combination of feeler mechanism for detecting variations in the thickness of a piece of sheet stock, skiving mechanism for said pieces of stock comprising a knife and two rolls for feeding the stock against the edge of said knife, one of said rolls being spring pressed toward the other, stops for limiting the movement of said spring pressed roll away from its companion roll, positive connections between said feeler mechanism and said stops for adjusting the stops in accordance with the thickness determinations made by said feeler mechanism, and means for locking said stops in their adjusted positions.

19. In a machine of the character described, the combination of feeler mechanism for detecting variations in the thickness of a piece of sheet stock, skiving mechanism for said pieces of stock comprising a knife and two rolls for feeding the stock against the edge of said knife, one of said rolls being spring pressed toward the other, stops for limiting the movement of said spring pressed roll away from its companion roll, positive connections between said feeler mechanism and said stops for adjusting the stops in accordance with the thickness determinations made by said feeler mechanism, pawl and ratchet mechanism for locking said stops in their adjusted positions, and power operated means for controlling the action of said pawl and ratchet mechanism.

20. In a machine of the character described, the combination of feeler mechanism for detecting variations in the thickness of a piece of sheet stock, skiving mechanism for said pieces of stock comprising a knife and two rolls for feeding the stock against the edge of said knife, one of said rolls being spring pressed toward the other, stops for limiting the movement of said

spring pressed roll away from its companion roll, positive connections between said feeler mechanism and said stops for adjusting the stops in accordance with the thickness determinations made by said feeler mechanism, means for locking said stops in their adjusted positions, and spring means acting on said connections to return them and said stops to their initial positions when the stops are unlocked.

21. In a machine of the character described, the combination of feeler mechanism for detecting variations in the thickness of a piece of sheet stock, said mechanism comprising two groups of feelers arranged to engage the work simultaneously, said feelers being individually movable in conformity to the thickness of the portions of the stock engaged thereby, means for supporting the stock while it is engaged by said feelers, two plates mounted for engagement with the feelers of said respective groups, springs acting on said plates to hold them normally in engagement with said feelers, connections between said plates causing them to move in unison, whereby both plates take a position determined by the feeler which engages the thinnest portion of the stock, additional mechanism for acting on the pieces of stock after they have been subjected to the operation of said feeler mechanism, and connections between said plates and said additional mechanism for adjusting said additional mechanism in accordance with the positions of said plates.

22. In a machine of the character described, the combination of feeler mechanism for detecting variations in the thickness of a piece of sheet stock, said mechanism comprising a series of feelers arranged to engage the stock simultaneously, said feelers being individually movable in conformity to the thickness of the portions of the stock engaged thereby and being operative to detect the thinnest portion of the stock so engaged, mechanism for automatically feeding pieces of stock one at a time into position for the engagement therewith of said feelers, a rigid support for the stock while it is engaged by said feelers, and means for preventing said pieces of stock from twisting while they are being fed into said position.

23. In a machine of the character described, the combination of a mechanism for detecting variations in the thickness of a piece of sheet stock comprising a series of independently movable feelers arranged in two groups, said feelers being mounted

closely adjacent to each other and positioned for the engagement simultaneously with the marginal portion of said piece of stock, supporting means for said feelers enabling the two groups to be adjusted toward and from each other, additional mechanism for acting upon the pieces of stock after the engagement therewith of said feelers, and connections between said feelers and said additional mechanism for controlling the operation of the latter mechanism in accordance with the thickness determinations made by said feelers.

24. In a machine of the character described, the combination of feeler mechanism for detecting variations in the thickness of a piece of sheet stock, said mechanism comprising a series of feelers arranged to engage the stock simultaneously and said feelers being individually movable in conformity to the thickness of the portions of the stock engaged thereby, mechanism for feeding pieces of stock one at a time into position for the engagement therewith of said feelers, a rigid table on which the stock is supported while it is engaged by said feelers, skiving mechanism for acting upon said pieces of stock after they have been engaged by said feelers, means for relatively moving said feeler mechanism and the respective pieces of stock into operative engagement with each other, and connections between said skiving mechanism and said feeler mechanism for automatically setting the skiving mechanism to cause it to split the stock to substantially the thickness of the thinnest portion thereof engaged by said feelers.

25. In a machine of the character described, the combination of feeler mechanism for detecting variations in the thickness of a piece of sheet stock, said mechanism comprising a series of feelers individually movable in conformity to the thickness of the portions of the stock engaged thereby, means for relatively moving said feelers and said stock into operative engagement with each other to enable said feelers to measure the thickness of the thinnest portion of the stock engaged by them while said feelers and stock are relatively stationary, mechanism for evening the pieces of stock so acted upon, and connections between said feeler mechanism and said evening mechanism for automatically controlling the action of said evening mechanism in accordance with said thickness determination.

GEORGE L. SMITH.
